HUMIDITY CONTROLLER

Frederick D. Joesting, Chicago, Ill., assignor to
Minneapolis-Honeywell Regulator Company,
Minneapolis, Minn., a corporation of Delaware

Application June 15, 1940, Serial No. 340,853

18 Claims. (CL 236—44)

The present invention relates to control devices and is more particularly concerned with providing a compact and accurate controller which responds to changes in humidity.

Another object is to provide a humidity control mechanism placed within a neat and decorative casing suitable for mounting upon a wall or elsewhere in a dwelling or other building.

A further object is to provide, in a control device, a simplified adjustment for varying the sensitivity or the differential of said device in its normal controlling operation.

Another object is to provide a simplified reversing arrangement for setting said device to actuate a controlled mechanism by either direct or reverse action, whichever is desired.

Another object is to provide a simplified strain release for the condition responsive element which is associated with the adjustment mechanism for the element.

A still further object is to provide means associated with the adjustment mechanism and the condition responsive element of a control device which will compensate for any movements of such element in response to temperature changes of the ambient air which is in contact with the device.

Still other objects will become apparent upon consideration of the following specification and claims, taken in view of the accompanying drawings, in which:

Figure 1 is an elevational view of a control instrument embodying the invention, the cover being in place.

Figure 2 is a view similar to Figure 1 with the cover removed.

Figure 3 is a section taken on line 3—3 of Figure 2.

Figure 4 is a section taken on line 4—4 of Figure 3, and

Figure 5 is a detailed sectional view of a part of my device.

Referring to Figures 2, 3, and 4, a base 20 has suitable mounting skirts 21 and upstanding ends 22. Disposed between the skirts 21 is a second smaller base 23 which is fastened to the skirts 21 by screws 24. Secured upon the smaller base 23 is a chamber 25 which has conventional passages therein which lead to an air supply line 26, a control line 27, and a bleed port 28 which is provided in an upstanding nipple 29. Also secured to the base 20 is a valve mechanism 30. The valve mechanism 30 has a flapper valve 31 which is pivoted at 32 upon shouldered pins 33 which are suitably secured to the base 20 by posts 34. 55

A biasing spring 35 bears against the upper surface of the flapper valve 31 and is adjustably secured in position by a bolt 36.

The flapper valve mechanism 30 is actuated by an adjustable lever mechanism 40. A first lever 41 is in the form of a bell crank pivoted upon horizontal pivot pins 42 which are secured to the right hand upstanding arm 22 of the base 20 as viewed in Figure 3. This lever 41 is retained upon the pins 42 by a small spring 49. The lever 41 has a lever arm 43 provided with an adjustment screw 44 which operatively engages the flapper valve 31. Lever 41 also has a second broad faced lever arm 45. This arm 45 is broad faced for purposes of adjustment to be hereinafter described. It will be noted with reference to Figure 3 that the lever arm 43 of the lever 41 will be rocked up and down upon movement of the other lever arm 45. A second lever 50 has a broad face 51 which is of substantially the same area as the broad faced lever arm 45 of the lever 41. The lever 50 has upper and lower ears 52 and 53. The upper ear 52 is pivoted upon a screw 54 which is secured to a bracket 55 which is in turn secured to the right hand upstanding arm 22 of the base 20. The lower ear 53 is in vertical alignment with the upper ear 52 and is pivoted to a screw 56 which is secured to the base 20 as is clearly shown in Figure 4. 30 It is seen that the lever 50 rotates about a vertical axis whereas the lever 41 rotates about a horizontal axis. However, it will be obvious that any suitable angle for the two axes may be used.

A pin 60 is provided to transfer movement from the lever 50 to the lever 41. This pin 60 is screw threaded and provided with a nut 61 which is tapped to provide a factory adjustment for the pin 60. This adjustment comprises screwing the pin 60 in or out within the nut 61 until the proper length of the pin 60 extends through the lever 50. After the device is adjusted a drop of solder 62 may be placed upon the nut 61 and the head of the pin 60 to thus form a unitary adjustment screw member. An adjustment nut 63 is disposed on the opposite side of the lever 50 in cooperative relation with the nut 61 and the pin 60. The adjustment screw member fits into the slot 65 or the slot 66. As shown in the drawings, the adjustment member is in the slot 65.

A typical adjustment may be obtained as follows: With reference to Figure 4 assume that a larger differential adjustment for the lever mechanism 40 is desired. The operator may loosen the nut 61 and slip the pin 60 upwardly in the slot 65 until the desired point is reached. The

nut 61 may then be tightened to secure the pin 60 in the new position. By this single adjusting movement the effective lever arm of both of the levers 50 and 41 will be changed. The lever 50 which rotates about a vertical axis as has been previously explained will have its effective lever arm shortened because the slot 65 slants upwardly toward this axis. The lever 41 which rotates about the horizontally aligned pins 42 will have its effective lever arm lengthened because the pin 60 will be moved away from its axis. By properly selecting differently slanting slots any desired ratio of change for these effective lever arms may be obtained.

Suitable indicia 50a are stamped upon the face of the lever 50. Indicia characters DA indicate the direct acting slot 66 and the characters RA indicate the reverse acting slot which, when the pin 60 is placed therein, acts just oppositely to the direct acting slot because these two slots are on different sides of the vertical pivots 54 and 56 for the lever 50. The action for lever 41 remains the same because the pin 60 will remain above the horizontal pivot pins 42.

A humidity responsive element 70 has several hair strands 71 which are secured at each end to clips 72. The right hand clip 72 is fastened to a pivot 73 which is rotatably secured to an ear 67 of the lever 50. The left hand clip 72 has a pin 74 which is rotatably secured to an ear 75a of an adjustment lever 75. Therefore it is seen that this humidity responsive element 70 is actively secured between the adjusting lever 75 and the operating lever 50. A main spring 68 secured to the ear 67 on the lever 50 and an arm 69 on the bracket 55 at all times biases the lever 50 in one direction and tensions the humidity responsive element 70 which tends to move the lever 50 in the opposite direction.

The adjustment lever 75 is pivoted at 76 to a temperature compensating rod 77. The rod 77 has a shoulder 78 which may cooperate with suitable pivot dimples on the lever 75 in a manner that is well known. The rod 77 is adjustably secured and is horizontally slidably within a hole in one end to a bracket 78 secured to the base 20 by screws 79. An adjustment nut 80 cooperates with a screw threaded portion 81 of the rod 77, thus providing a factory adjustment of the position of the pivot point 76. The other end 82 of the rod 77 is screw threaded and equipped with a nut 83 and a spring 84 to provide a strain release connection for the humidity responsive element 70. The end 82 extends loosely through the left hand arm 22 of the base 20 so that if the humidity responsive element 70 should shrink beyond the degree to which it is adjusted, the entire rod 77 would be free to move toward the right against the action of the strain release spring 84. The rod 77 may be made of brass or any other suitable temperature responsive material and is adapted to compensate the humidity responsive element 70 for any changes in ambient temperature to which the element 70 is subjected. It is also seen that, by combining this temperature compensating feature with a spring biased pivot for an adjustment lever, a simplified structure providing temperature compensation, a strain release, and an adjustment is obtained.

An adjustment mechanism 90 is provided to vary the control point for the humidity responsive element 70. This adjustment mechanism 90 has a main adjustment screw 94 which is provided with an enlarged shoulder 95 and a

reduced neck 96. The shoulder 95 is pressed against the inner surface 97 of the left hand arm 22 of the base 20 by a spring clip 98 which engages a tapered portion 99 of the screw head 93 and the outer surface of the arm 22. A pin 100 is suitably secured in a recess 101 in the shoulder 95. The pin 100 is slidably received in a hole 102 in an annular flange 103 of a sleeve 104. The pin 100 imparts rotary motion from the shoulder 95 of the screw 94 to the annular flange 103, thereby rotating the screw 94 and the sleeve 104 simultaneously. A sleeve 105 is provided with external screw threads 106 which cooperate with internal screw threads 107 of the outer sleeve 104. The sleeve 105 is provided with internal threads 108 which cooperate with threads 109 on the screw 94. The pitches of the internal and external threads of this sleeve 105 are both right hand threads in the particular modification shown. The purpose of these different threads will be more fully described hereinafter. The sleeve 105 is non-rotatably secured to an arm 110. The top of the arm 110 is provided with an indicator 13 which may be painted or suitably stamped so as to be readily seen. A downturned ear 111 is provided with a hole 112 through which a guide arm 113 slidably extends. The arm 113 is secured to a bracket 114 which is suitably secured by a depending arm 115 to the upstanding arm 22 of the base 20. The bracket 114 has indicia stamped thereon so that the device may be readily adjusted in the factory or for installation settings while the cover is off.

A cover 10 is attached to a mounting skirt 11 by suitable means. The cover 10 has a slot 12 through which the adjustment indicator 13 is visible. The adjustment indicator 13 cooperates with a scale 14, the indicia of which are impressed upon a depressed portion 15 of the cover 10. The indicia upon the portion 15 are identical to the indicia upon the bracket 114, hereinbefore mentioned. In many installations, covers without slots are provided, in which case the device is set with the cover removed in accordance with the indicia on the bracket 114.

A detailed sectional view of the adjustment mechanism 90 is shown in Figure 5. A portion of the case 10 is shown in this figure which has a hole 92 that registers with an adjustment nut 93. This hole 92 is adapted to allow passage of a suitable socket wrench which may engage the nut 93 to provide for manual adjustment of the device.

To adjust the humidity responsive element 70 to operate at different humidities, a suitable wrench may be inserted through the hole 92 in the cover 10 and engage the nut 93. Upon rotation of the nut 93 in a clockwise direction, the screw threaded stem 94 will be likewise rotated in a clockwise direction. Because the pin 100 which is secured to the shoulder 95 extends through the hole 102 in the annular flange 103 of the sleeve 104, this sleeve 104 will likewise be rotated in a clockwise direction. Upon such rotation the screw threads 106 and 107 will tend to move the sleeve 104 toward the right in relation to the non-rotatable sleeve 105. However, clockwise movement of the screw threads 109 will tend to move the sleeve 105 toward the left. By properly selecting differently pitched threads, a difference in rate of movement of these two sleeves may be obtained. In other words, for example, if the exterior of the threaded sleeve 106 has thirty-two threads per inch and the interior

has thirty threads per inch, for an inch of movement in one direction of the threaded sleeve 105 the external sleeve 104 would move axially in the same direction only the equivalent of two threads, or one-sixteenth of an inch. Therefore the adjustment shoulder 120 which is integral with the sleeve 104 and upon which the adjustment arms 91 of the lever 15 bear will be moved only one-sixteenth as far as the indicator 13 which is carried by the threaded sleeve 105. Also, because the arms 91 engage the shoulder 120 at about twice the distance from the pivot point 76 with respect to distance which the humidity element 70 is connected to the ear 75, the actual ratio of movement between the indicator 13 and the humidity element 70 is about thirty-two to one. Of course some other suitable ratio could be used if desired. It will be obvious that by rotating the nut 93 in a counter-clockwise direction, the reverse of the action above described will be effected.

It will be understood that many other differential movements may be obtained by selecting different thread pitches or changing the pitch direction, as from right hand to left hand threads. One example of a reversing differential movement could be accomplished as follows: Assume that the internal threads 108 are thirty-two pitch to the inch, and the external threads 106 are thirty pitch (both threads being right hand). Now if the screw 94 is rotated so as to move the threaded sleeve 105 one inch toward the right, thirty-two revolutions thereof will be necessary. Because the pin 100 carried by the shoulder 95 of the screw 94 is operatively connected to the external sleeve 104, this sleeve likewise will be rotated. Thirty-two revolutions of the exterior sleeve 104 will cause this sleeve to move thirty-two thirtyths of an inch toward the left, or one and one-fifteenth inches relative to the threaded sleeve 105. Thus it is apparent that in moving the threaded sleeve 105 one inch toward the right, the external sleeve 104 will be moved one-fifteenth inch toward the left. This shows that various amounts of travel, or reversed direction travel, may be obtained by properly selecting differently pitched screw threads.

Operation

It has been previously pointed out that the present device is adapted to control the relative humidity in a space to be either humidified or de-humidified. It has also been explained that the device may be made either direct or reverse acting by merely changing the position of the actuating nut 61 between the adjustment slots 65 or 66 as desired.

Assuming then that the parts of the device are in the position illustrated, the flapper valve member 31 is held away from the valve port 28 by the lever arm 43. With the adjustment nut 61 in the position shown, the valve is opened upon an increase in humidity which causes the humidity responsive strands 71 to stretch. When these strands 71 stretch, the main spring 68 biases the lever 50 in a counter-clockwise direction as viewed in Figure 2. As the lever 50 is rotated in a counter-clockwise direction, the pin 60 will bear against the broad faced arm 45 of the lever 41 and rotate this lever 41 in a clockwise direction as viewed in Figure 3. Therefore it is seen that the lever arm 43 will be raised to lift the flapper valve 31 away from the bleed port 28 by the main spring 68 upon an increase in humidity.

Upon a decrease in humidity, the humidity responsive strands 71 will shrink and rotate the 75

lever 50 in a clockwise direction against the action of spring 68 as viewed in Figure 2. When the lever 50 is rotated in a clockwise direction the pin 60 will allow the spring 35 on the flapper valve 31 to bias the lever arm 43 downwardly until the flapper valve 31 engages the bleed port 28.

It will be noted that the adjustment screw 61 is about in the mid point of the slot 65 as viewed in Figure 4. At this point of adjustment, the device will be at some predetermined intermediate point between maximum and minimum differential adjustment. By differential adjustment is meant the difference in relative humidity response necessary to open and close the valve bleed port 28 a sufficient amount to fully operate the device controlled. To adjust the device to have a maximum differential as has been hereinbefore explained, the pin 60 may be moved toward the top of the slot 65, and for minimum differential, the pin 60 may be moved to the bottom of the slot 65. It will be noted that when the pin is in the upper position, the effective lever arm of the lever 50 which acts upon the portion 45 of the lever 41 will be reduced. In other words, the pin 60 will be closer to the center of rotation of the lever 50. Also, with the pin 60 in the top of the slot 65, that pin will engage the lever 45 at a point a greater distance away from its pivots 42. For the lower position of the pin 60 the opposite relationship obtains. As has been previously pointed out, the variations for the relative lever arms for each lever may be selected as desired by using slots having different angles in relation to the levers.

With the device as shown, one of the effective lever arms is decreased as the other is increased to thereby obtain an effectively large adjustment. With the slot and lever arranged as illustrated in the drawings, it has been found that a change in lever ratios of approximately between one to one and fifteen to one can be obtained as the pin 60 is moved from one end of the slot to the other.

If it is desired to make the device direct acting, the adjustment pin 60 may be changed over to the slot 66 by merely removing the nut and placing the parts in the slot 66. It will be clear from reference to Figure 4 that the differential adjustment of the device will be identical. With the device direct acting, when the relative humidity which affects the strands 71 increases and causes them to stretch, the lever 50 will be rotated in a counter-clockwise direction, as viewed in Figure 2, by the main spring 68. The pin 60 now being on the opposite side of the pivots 54 and 56, the pin will move away from the broad faced lever arm 45 of the lever 41. It will be seen by referring to Figure 3, that when the pin 60 is moved away from the lever arm 45 the lever arm 43 will be forced downwardly by the spring 35 which acts upon the flapper valve 31 to thus close the bleed port 28.

When the relative humidity which affects the strands 71 decreases, these strands will shrink to rotate the lever 50 against the bias of the main spring 68 in a clockwise direction. The pin 60, now being in the slot 66, will rotate the lever arm 45 in a clockwise direction as viewed in Figure 3, and raise the lever arm 43 to move the flapper valve 31 away from the bleed port 28.

It is seen that I have provided a humidity responsive device which may be either direct or reverse acting as desired. It is also noted that I have provided a differential adjustment for such a device which is adjusted in the same

manner whether the device is direct acting or reverse acting. I have also provided a temperature compensating arrangement including a strain release connection in combination with a simplified adjustment device which gives different ranges of movement to an adjustment element and an indicator which cooperates with suitable indicia.

Many forms and modifications of my device will occur to those skilled in the art. Therefore it is to be clearly understood that I am not to be limited in my invention only to that form shown and described, but by the spirit and scope of the appended claims.

I claim as my invention:

1. In a control device, in combination, a first lever pivoted to rotate about a first axis, a second lever pivoted to rotate about a second axis, said first and second axes being in angular relationship to each other, adjustable connecting means to transmit movement from one to the other of said levers movable angularly in relation to the axes of both levers to simultaneously vary an effective lever arm of each lever, control means operated by one of said levers, condition responsive means to move the other of said levers, and adjustment means for adjusting the condition value at which said condition responsive means will move said other lever.

2. In a control device, in combination, a first lever pivoted to rotate about a first axis, a second lever pivoted to rotate about a second axis, said first and second axes being in angular relationship to each other, connecting means to transmit movement from one to the other of said levers, adjustment means movable angularly in relation to the axes of both levers to simultaneously vary an effective lever arm of each lever, condition responsive means to move one of said levers, and means for changing said connecting means from one to the other side of the axis of one of said levers to cause said device to be either direct or reverse acting.

3. In a control device, in combination, a first lever pivoted to rotate about a first axis, a second lever pivoted to rotate about a second axis, said first and second axes being in angular relationship to each other, connecting means to transmit movement from one to the other of said levers, adjustment means movable angularly in relation to the axes of both levers to simultaneously vary an effective lever arm of each lever, condition responsive means to move one of said levers, control means operated by the other of said levers, and means for changing said connecting means from one to the other side of the axis of one of said levers to cause said control means to be either direct or reverse acting with respect to said condition responsive means.

4. In combination, a non-rotatable first sleeve having interior and exterior threads, said interior threads being of a different pitch with relation to the said exterior threads, a rotatable second sleeve having interior threads cooperable with the exterior threads of said first sleeve, a screw cooperable with the interior threads of said first sleeve, means to rotate said screw and said second sleeve simultaneously whereby said first sleeve and said second sleeve move at different rates of movement in axial relationship to said screw in accordance with the difference in pitch of said interior and exterior threads, first adjustment means actuated by one of said sleeves, and second adjustment means actuated by the other of said sleeves.

5. In combination, a non-rotatable first sleeve having interior and exterior threads, said interior threads being of a different pitch with relation to said exterior threads, a rotatable second sleeve having interior threads cooperable with the exterior threads of said first sleeve, a screw cooperable with the interior threads of said first sleeve, means to rotate said screw and said second sleeve simultaneously whereby said first sleeve and said second sleeve move at different rates of movement in axial relationship to said screw in accordance with the difference in pitch of said interior and exterior threads, first adjustment means actuated by one of said sleeves, second adjustment means actuated by the other of said sleeves, an indicator carried by one of said adjustment means, a cover having a hole therein which registers with said indicator, and indicia adjacent the hole in said cover for indicating the position of said adjustment means.

6. In combination, a pair of spaced supports, a bleed port secured between said supports, a flapper valve cooperable with said bleed port, a movable humidity responsive element, connection means between said element and said valve whereby said valve is moved toward and away from said port by said element, said connection means including a pair of non-parallelly rotatable levers, and adjustment means to vary the effective lever arm of at least one of said levers to thereby vary the sensitivity of said valve in response to movement of said element.

7. In combination, a pair of spaced supports, a bleed port secured between said supports, a flapper valve cooperable with said bleed port, a movable humidity responsive element, connection means between said element and said valve whereby said valve is moved toward and away from said port by said element, said connection means including a pair of non-parallelly rotatable levers, adjustment means to vary the effective lever arm of at least one of said levers to thereby vary the sensitivity of said valve in response to movement of said element, and adjustment means for adjusting the control point of said element.

8. In combination, a pair of spaced supports, a bleed port secured between said supports, a flapper valve cooperable with said bleed port, a movable humidity responsive element, connection means between said element and said valve whereby said valve is moved toward and away from said port by said element, said connection means including a pair of non-parallelly rotatable levers, adjustment means to vary the effective lever arm of at least one of said levers to thereby vary the sensitivity of said valve in response to movement of said element, adjustment means for adjusting the control point of said element, and temperature compensating means for compensating the movement of said element in response to temperature changes.

9. In combination, a pair of spaced supports, a bleed port secured between said supports, a flapper valve cooperable with said bleed port, a movable humidity responsive element, connection means between said element and said valve whereby said valve is moved toward and away from said port by said element, said connection means including a pair of non-parallelly rotatable levers, adjustment means to vary the effective lever arm of at least one of said levers to thereby vary the sensitivity of said valve in response to movement of said element, adjustment means for adjusting the control point of said ele-

ment, and strain release means associated with said adjustment means to protect against undue stress in said element.

10. In combination, a flapper valve, a movable humidity responsive element for opening and closing said flapper valve in accordance with changes in ambient humidity, first adjustment means for varying the sensitivity of said element in relation to said valve, second adjustment means for varying the control point at which said element will act upon said valve, a strain release for preventing undue stress in said element, and means for preventing movement of said element in response to ambient temperature changes, said last means also providing a pivot for said adjustment means.

11. In combination, a flapper valve, a movable humidity responsive element for opening and closing said flapper valve in accordance with changes in ambient humidity, first adjustment means for varying the sensitivity of said element in relation to said valve, a rotatable adjusting screw, a pair of axially movable adjustment sleeves carried by said screw, variously pitched screw thread means causing one of said sleeves to move a greater distance than the other for the same rotation of said adjusting screw, an indicator carried by one of said sleeves for indicating the setting of the element, a lever adapted to be positioned by the other of said sleeves for setting said element, a pivot for said lever, and temperature compensating means associated with said pivot for compensating the movement of said element in response to ambient temperature changes.

12. A control device adjustment comprising, an actuating first lever pivoted to rotate about an axis, an actuated second lever pivoted to rotate about an axis which is in angular relationship to said first axis, connecting means for connecting said two levers, said connecting means being adjustable to vary the effective lever arm of at least one of said levers, and means for changing said connecting means from one to the other side of the axis of one of said levers only to thereby reverse the effective action of said one of said levers.

13. In a control device, in combination, a first lever pivoted to rotate about a first axis, a second lever pivoted to rotate about a second axis, said first and second axes being in angular relationship to each other, adjustable connecting means to transmit movement from one to the other of said levers movable angularly in relation to the axes of both levers to simultaneously vary an effective lever arm of each lever, condition responsive means to move one of said levers, and means for positioning said connecting means on either side of the axis of one of said levers to cause the device to operate either direct or reverse acting.

14. In a humidity responsive control device, in combination, a base member, a control element carried by said base, a longitudinally expanding and contracting humidity responsive element having a coefficient of thermal expansion differing from that of the material of which said base member is composed operatively connected at a first end to said control element, a temperature compensating member carried at one of its ends by said base and having a free end adapted to move relative to said base on changes in temperature, and a support for the second end of said humidity responsive element, the

free end of said compensating member engaging said support and operating to move said support away from the first end of said humidity responsive element on an increase in temperature to compensate for thermal expansion of said humidity responsive element.

15. In a control device, in combination, a first lever pivoted to rotate about a first axis, a second lever pivoted to rotate about a second axis, said first and second axes being in angular relationship to each other, adjustable connecting means carried by said first lever to transmit movement from one to the other of said levers, releasable means for securing said connecting means to said lever at a plurality of positions providing different leverages between said levers and condition responsive means to move one of said levers.

16. In a control device, in combination, a first lever pivoted to rotate about a first axis, a second lever pivoted to rotate about a second axis, said first and second axes being in angular relationship to each other, condition responsive means for moving said first lever, control means actuated by said second lever, motion transmitting means connecting a first point on said first lever with a first point on said second lever, and means for adjusting the effective leverage of said levers comprising means for bodily adjusting said motion transmitting means to connect a second point on said first lever with a second point on said second lever.

17. In a humidity responsive control device, in combination, a base member, a control element carried by said base, a longitudinally expanding and contracting humidity responsive element having a coefficient of thermal expansion differing from that of the material of which said base member is composed operatively connected at a first end to said control element, a temperature compensating member carried at one of its ends by said base and having a free end adapted to move relative to said base on changes in temperature, a lever, adjusting means for positioning a first end of said lever to select the value of relative humidity at which said control element is operated, and a support for the second end of said humidity responsive element carried by the second end of said lever, said lever being pivoted intermediate its ends on the free end of said compensating member.

18. In a humidity responsive control device, in combination, a base member, a control element carried by said base, a longitudinally expanding and contracting humidity responsive element having a coefficient of thermal expansion differing from that of the material of which said base member is composed operatively connected at a first end to said control element, a temperature compensating member carried by said base member and having one of its ends biased to a predetermined position with respect to said base member, the other end of said compensating member being free to move relative to said base member on changes in temperature, a lever, adjusting means for positioning a first end of said lever to select the value of relative humidity at which said control element is operated, and a support for the second end of said humidity responsive element carried by the second end of said lever, said lever being pivoted intermediate its ends on the free end of said compensating member.

FREDERICK D. JOESTING.
